COMBINED MEDICINE DROPPER AND SWAB

Abraham E. Massman, Lufkin, Tex.

Application May 14, 1936, Serial No. 79,819

8 Claims. (Cl. 128—269)

This invention relates to medicine applicators and more particularly to a device especially designed for use in the treatment of nasal ailments such as head colds, hay fever, sinusitus 5 and for nasal hygiene in general.

The object of the invention is to provide an applicator of simple and inexpensive construction which may be used with equally good results either as an ordinary medicine dropper or 10 as a nasal swab for washing and cleaning the nasal passages and for applying medicament in liquid form directly to the mucous membrane of the affected parts.

A further object of the invention is to provide a medicine applicator which may be charged 15 with a predetermined quantity of liquid medicament for delivery to the swab when required, thereby keeping the swab saturated with medicament and permitting continued use thereof without the necessity of constantly dipping or immersing the swab within a medicine container.

A further object is to provide a medicine applicator including a tube having a compressible bulb at one end thereof and a perforated substantially spherical tip at the other adapted to receive a quantity of cotton or other absorbent material; means being provided for detachably securing the cotton in position on the tip to 25 permit ready removal of said cotton when it is desired to convert the swab into a medicine dropper.

A further object is to provide novel means for clamping the cotton or absorbent material on the perforated tip of the tube, said means comprising a collar slidably mounted on the tube and movable into engagement with the absorbent material for forcing said absorbent material around a constricted neck of the tube.

A still further object of the invention is generally to improve this class of devices so as to 40 increase their utility, durability and efficiency.

In the accompanying drawing forming a part 45 of this invention and in which similar numerals of reference indicate corresponding parts in all the figures of the drawing,

Figure 1 is a vertical sectional view of a medicine bottle equipped with an applicator constructed in accordance with the present invention.

Figure 2 is a side elevation of the applicator 50 removed from the bottle and showing the position of the clamping collar when the device is used as a medicine dropper.

Figure 3 is a similar view showing the position 55 of the parts when the device is used as a swab.

The improved medicine applicator forming the subject-matter of the present invention is especially designed for use in connection with bottles and other medicine containers and by way 60 of illustration is shown applied to a medicine bot-

tle of standard construction, in which 5 designates the body of the bottle and 6 the neck, the exterior walls of which are threaded, at 7, for engagement with a detachable cap, indicated at 8. The cap 8 is provided with a compressible bulb 9, and fitted in a groove 10 in the inner wall of the bulb 9 is the flanged end 11 of a depending tube 12.

The tube 12 is preferably formed of glass and of sufficient length to extend to a point near the bottom of the bottle so that the lower end thereof will be immersed in the liquid medicament at practically all times. The lower end of the tube 12 is pressed, molded or otherwise formed with a substantially spherical tip 13 provided with 15 a central perforation 14 through which the medicament or other liquid within the container 5 may be discharged within the nasal passages when the device is to be used as a medicine dropper. The exterior walls of the globular tip 20 13 are smooth and unobstructed so that the tip will not lacerate or irritate the delicate lining of the nasal passages when the applicator is inserted therein for the purpose of applying medicament to the effected parts. The side walls of 25 the tube 12 at a point immediately above the tip 13 are pressed inwardly to form a constricted neck 15 adapted to receive a strip of cotton gauze or other absorbent material 16 when the device is to be used as a swab. 30

Slidably mounted on the tube 12 is a clamping collar 17 preferably formed of silver or other material not affected by the medicine within the bottle 5. The lower end of the collar 17 is flared laterally to form a bell-shaped mouth 18 and the side walls of said collar are provided with tapered ribs 19 which coat with a clamping ring 20 for the purpose of holding the collar in a set position on the tube. 35

The cotton or gauze strip 16 extends over the 40 perforation 14 in the tip and entirely surrounds said tip with the end portion of the strip seated within the neck 15 so that when the collar 17 is moved longitudinally of the tube, the bell-shaped mouth thereof will fit over the absorbent material and press the latter within the neck 15 and in which position it will be securely clamped by sliding the ring 20 over the ribs 19 of the collar. 45

When the device is to be used as a medicine dropper, inward pressure is exerted on the bulb 9 which sucks some of the liquid within the end of the tube, after which the cap 8 with the tube in position thereon is removed from the bottle 5. The head is then thrown back and the tip introduced within the nasal passage and the liquid deposited therein by pressing the bulb 9 as will be readily understood. 50

When the device is used as a swab for washing and cleaning the nasal passages or for applying medicament in liquid form directly to the mucous 55 60

membrane of the affected parts, the bulb 9 is compressed so as to fill or partially fill the tube 12 with medicament. The tube is then removed from the bottle 5 and the tip of the tube covered 5 with the absorbent material 16, the collar 17 being then adjusted longitudinally of the tube 12 so as to clamp the absorbent material within the neck 15 and in which position it is retained by the ring 20, as previously stated. The applicator with the absorbent cotton in position thereon is then inserted within each nasal passage and rotated, or partially rotated, so as to thoroughly clean said passages and apply the medicament to the mucous membrane thereof. By 10 compressing the bulb 9, the charge of medicine within the tube 12 may be deposited on the absorbent material at will so that the absorbent material or swab will be kept continuously saturated without the necessity of dipping the swab 15 within the liquid in the bottle from time to time to accomplish this purpose. If desired, however, instead of filling the tube 12 with medicament before applying the absorbent material, said tube may be removed from the bottle 5 and the absorbent material then applied to the tip, in which 20 event the liquid will be drawn within the tube through the absorbent material. After the swab 16 has served its purpose, the clamping ring 20 is slid off the collar 17 and the latter moved longitudinally of the tube 12 until the flared end 18 of the collar clears the absorbent material when 25 said absorbent material may be readily detached from the tip and thrown away. Inasmuch as the ring 20 serves to clamp the collar on the tube, it follows that said collar may be held at any desired position of longitudinal adjustment on the tube so as not to interfere with the device when 30 used as medicine dropper.

Attention is here called to the fact that the 40 diameter of the tip 13 is slightly greater than the diameter of the body of the tube 12 so that the tip 13 acts as stop and prevents the collar and its associated parts from being accidentally detached from the tube.

45 It will thus be seen that the applicator serves the dual function of a medicine dropper and as a swab for washing and cleaning out the nasal passages and in addition thereto provides a means for applying medicament in the desired quantities on the surface of the affected parts. 50 It will, of course, be understood that the devices may be made in different sizes and shapes and constructed from any suitable material without departing from the spirit of the invention.

Having thus described the invention, what is 55 claimed as new is:

1. A medicine applicator comprising a tube having an enlarged substantially spherical tip provided with a discharge perforation, exterior walls of the tip and the perforation therein being 60 adapted to be covered by absorbent material and a collar slidably mounted on the tube and movable into engagement with the absorbent material for clamping the latter in position on the tip.

65 2. A medicine applicator comprising a tube having one end thereof provided with a substantially globular tip having a discharge perforation therein, a compressible bulb at the other end of the tube, exterior walls of the tip and the perforation therein being adapted to be covered by 70 absorbent material, and means mounted on the tube and engaging the absorbent material for holding the latter in position on the tip.

3. A medicine applicator comprising a tube having a substantially globular tip provided with a discharge perforation the tip and adjacent portions of the tube being adapted to be enclosed with absorbent material covering the tip and the perforation therein, and a clamping device slidably mounted on the tube for engaging the absorbent material, said clamping member being movable to inoperative position to release the absorbent material and expose the discharge perforation to permit the tube to be used as a medicine dropper. 5

4. A medicine applicator comprising a tube adapted to receive a predetermined charge of medicine, an enlarged substantially spherical shaped tip disposed at one end of the tube and provided with a discharge perforation, exterior walls of the tip and the perforation therein being adapted to be covered by absorbent material, means slidably mounted on the tube for engaging the absorbent material and holding the absorbent material on the tip, and a compressible bulb at the other end of the tube for feeding the charge of medicine through said perforation to the absorbent material. 10

5. A medicine applicator including a tube having one end thereof provided with a constricted neck terminating in a substantially spherical perforated tip, whereby absorbent material covering the tip and said neck may have a portion engaged 30 in the neck, a collar slidably mounted on the tube for engaging the absorbent material and forcing the latter within the constricted neck, and means for holding the collar in a set position on the tube, the diameter of the tip being greater than 35 the tube to prevent displacement of the collar. 45

6. A combined swab and medicine dropper including a tube adapted to receive a charge of medicine, a perforated tip at one end of the tube adapted to be covered by absorbent material extending over the perforation therein, a collar slidably mounted on the tube and adapted to engage the absorbent material for clamping the material in position on the tube, and means at the other end of the tube for feeding the medicine through said perforation to the absorbent material. 50

7. A medicine applicator comprising a tube, a compressible bulb at one end of the tube, a perforated tip at the other end of said tube, a collar slidably mounted on the tube and movable into position to engage about absorbent material and hold the absorbent material about the perforated tip of the tube, inclined ribs formed on the collar, and a clamping ring adapted to engage the ribs for holding the collar in a set position on the tube. 55

8. A medicine applicator comprising a tube, a compressible bulb at one end of the tube, a substantially spherical perforated tip at the other end of said tube and defining a constricted neck adapted to receive a portion of absorbent material entirely covering the tip and the perforation therein, a collar slidably mounted on the tube having its lower end flared laterally to form a bell-shaped mouth and its side walls provided with inclined longitudinal ribs, said collar being movable into position to engage about the absorbent material for clamping the latter within the neck, and a ring fitted over the collar and adapted to engage the ribs for holding said collar in a set position. 60
